SIDE WALL FOR RAILWAY HOPPER CARS

Garth G. Gilpin, Chicago, Ill., assignor to Standard Railway Equipment Manufacturing Company, Chicago, Ill., a corporation of Delaware

Application February 17, 1944, Serial No. 522,806

5 Claims. (Cl. 105—409)

1

This invention relates to open top railway cars, such as hopper and gondola cars, and more specifically to an improved form of vertical wall therefor.

The vertical walls of such cars form girders for carrying the load, between the opposite body holsters, and also a retaining wall for the lading.

It is generally conceded that a hollow, seamless, tubular metallic section is about the strongest metallic shape under compressive and beam stress, and it is an object of the present invention to form the vertical posts of my car wall of such metallic section.

Another object of the invention is to form the vertical wall sheets of the car in a manner to provide the greatest carrying capacity for the car, and which plates are adaptable for cooperative use with said tubular posts.

A further object of the invention is to adapt the invention for the repair of walls of a hopper or gondola car, utilizing the side sill of such cars to form part of the bottom chord of the car wall.

A still further object of the invention is to form the edges of the side plates with flanges which surround the posts, thereby protecting same against the abrasive action of certain types of lading during loading and unloading and the action of acids in other types of lading when wet.

Still other objects and advantages of the invention will appear in the following description thereof.

Referring now to the accompanying drawings forming part of the invention and wherein like reference characters indicate like parts:

Fig. 1 is a side elevation of part of a hopper car side embodying my invention.

Fig. 2 is a longitudinal cross sectional view on the line 2—2 of Fig. 1.

Fig. 3 is a vertical cross sectional view on the line 3—3 of Fig. 1.

Fig. 4 is an enlarged view of the upper portion of Fig. 3.

Fig. 5 is an enlarged view of the lower portion of Fig. 3.

Fig. 6 is a longitudinal section of a portion of the car wall through one of the posts thereof, on the line 6—6 of Fig. 5.

Fig. 7 is a perspective sectional view on the line 7—7 of Fig. 1 in the direction of the arrows.

Fig. 8 is a perspective view of the bolster post.

As shown in the drawings, my improved wall comprises a plurality of longitudinally spaced vertical tubular posts 1, being preferably rectangular in cross section. These posts are slotted on opposite sides, as at 2, from the bottoms there-

of upwardly a distance sufficient to straddle the vertical leg 3 of the side sill of the car, and to which said posts are welded on both sides, as indicated at 4, Fig. 5. The side sill is of angle iron structure, having the horizontally disposed leg 5, which side sill, of course, extends from bolster to bolster of the car and is attached to the under-frame thereof as is common practice and forms the bottom chord member of the car wall. The bottom edge of said post is welded to the horizontal leg of the side sill, as shown in Fig. 5. The several posts extend upwardly the desired height and are notched out at their upper outer corners, as at 6, to receive the downwardly extending outer bulb 7 of the upper chord member, which is provided with a horizontally disposed web 8 and a vertically disposed arm 9. The bulb 7 is welded to the edges of the notch 6, as indicated in Fig. 4; and the arm 9 is similarly attached to the upper end of the inner face of the several posts. Thus a strong upper chord member is provided.

The side wall sheets 10 are somewhat similar to those described and claimed in my earlier Patent No. 2,030,748, of February 11, 1936, wherein said sheets span the space between the posts and the top and bottom chord members and are secured thereto to form the web of the girder and the load retaining means of the car. The posts form stiffeners for the web of the girder and act as vertical beams to transmit horizontal loads thereon to the frame members. The side wall sheets 10 are formed from flat metallic plate and are trimmed to a rectangular blank which in length is sufficient to span the space between the posts, provide a flange the width of the posts, and a reflare of approximately one-half the thickness of the post, all as shown most clearly in Figs. 2 and 6. The flanges of the sheets 10 are shown at 11, and the reflanges at 12; the flanges 11 abutting and being secured to the sides 13 of the posts, and the reflanges 12 overlapping and being secured to the inner edges 14 of said posts. See Fig. 6. Any vertical space between the meeting edges of the reflanges may be filled with welding material so that all surfaces of the posts which are subject to wear, abrasion or corrosion from the lading is protected therefrom by the wall sheets. The plates are slit from the top and bottom thereof on a vertical line coincident with the right-angular bend in the plate which forms the flanges 11, and the intermediate portion 15 at the upper end of the plate is bent diagonally inwardly, as shown in Figs. 3 and 4, to the plane of the vertical arm 9 of the top chord, where the plate is bent upwardly forming

a vertical flange 16 which is riveted as at 17, or otherwise secured to said arm 9. The diagonal edges of the intermediate portion 15 may be welded to the flanges 11, as indicated at 18. It is obvious that with this construction there will occur a relatively small opening 19 between the flange 11 and edge of the intermediate portion 15 at the upper inner corner thereof, and which may be filled with welding material to make a tight car wall for granular lading. It will be noted from Figs. 3 and 4 that the upper edges of the flanges 11 terminate in a plane with the lower edge of the depending arm 9 of the top chord.

The intermediate portion of the plates between the slits extending upwardly from the bottom of the plates is similarly bent inwardly diagonally, as shown at 20, Figs. 3 and 5, to the plane of the outer surface of the vertical leg 3 of the bottom sill or chord member, at which plane the plate is bent downwardly parallel to and abutting said leg 3 to which it is riveted, as at 21, or otherwise secured thereto.

The outer surfaces of the main portion of the wall sheets, between the diagonal portions 15 and 20 thereof, is disposed in the same vertical plane as the outer edges of the several posts, thereby presenting a smooth outer surface to the car wall, yet interiorly of the car the wall has the appearance of a paneled wall, which panels increase the carrying capacity of the car.

Fig. 7 shows a fragmental perspective view of the outside of the car wall illustrating the bolster post 25 of the car, which occurs near the end of the car where the bottom thereof tapers upwardly, as at 26, as is common in hopper cars. The side sill 3—5 of the car terminates at the bolster post, as indicated in Fig. 1, and as shown in Fig. 8, the outside of the lower end of the post is cut away, on a plane with the inside of the upstanding leg 3 of the side sill, leaving a channel-shaped section, the edges of the flanges of which channel section are welded to the leg 3 of the side sill. That portion of the post which extends below the inclined floor of the car is thus cut-away, and from a point approximately midway between the ends of the post 25, a channel 27 is formed therein, which extends downwardly to the cut-away portion, as clearly shown in Fig. 8. This channel 27 is for the purpose of admitting the inwardly disposed flanges 28 of a pair of reinforcing angle bars 29, which angle bars are formed to fit the contour of the bolster post 25, all as shown in Fig. 7. The other flanges of the angle bars overlap the outer surface of the post and are secured thereto and below the floor of the car said flanges are widened, as indicated at 30. A relatively large channel 31 is provided which forms a continuation of the side sill and extends from the bolster of the car to the end post 32 thereof. The upper flange of said channel at the inner end thereof is flattened to the plane of the web thereof, as indicated at 33, and secured to the flanges 30 and flange 3 of the side sill.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A wall for a railway car comprising a bottom chord having an upstanding leg, spaced hol-

low non-circular posts having the lower ends thereof slotted and straddling said leg and secured thereto on both sides thereof, and a wall sheet having the major portion thereof substantially in the plane of the outside of said post, the lower margin of said wall sheet bent inwardly and secured to said leg, said wall sheet extending between and secured to said posts.

2. A wall for a railway car comprising a girder comprising a top chord having a vertical arm and a horizontal arm extending outwardly therefrom, a bottom chord having a vertical leg and a horizontal leg extending inwardly therefrom, said vertical arm and vertical leg being in spaced vertical planes, spaced substantially rectangular tubular posts with the upper ends thereof overlapping and secured to said vertical arm, the lower ends of said posts being slotted and straddling said vertical leg and secured to both sides thereof, and wall sheets with the major portions thereof substantially in the plane of the outside of said posts and the upper and lower margins thereof bent inwardly and secured to the top chord and bottom chord, respectively, the side margins of said sheets having vertical flanges which overlap the sides of adjacent posts, said vertical flanges having reflanges which overlap the inner sides of said posts.

3. A wall for a railway car comprising a girder comprising a top chord having a vertical arm and a horizontal arm extending outwardly therefrom, a bottom chord having a vertical leg and a horizontal leg extending inwardly therefrom, said vertical arm and vertical leg being in spaced vertical planes, spaced substantially rectangular tubular posts with the upper ends thereof overlapping and secured to said vertical arm and also secured to said horizontal arm, the lower ends of said posts being slotted and straddling said vertical leg and secured to both sides thereof and also secured to said horizontal leg, and wall sheets with the major portions thereof substantially in the plane of the outside of said posts and the upper and lower margins thereof bent inwardly and secured to the top chord and bottom chord, respectively, the side margins of said sheets having vertical flanges which overlap the sides of adjacent posts, said vertical flanges having reflanges which overlap the inner sides of said posts.

4. A wall for a railway car comprising a bottom chord having an upstanding leg, spaced tubular posts having the lower ends thereof slotted and straddling said leg and secured thereto on both sides thereof, and a wall sheet having the major portion thereof substantially in the plane of the outside of said posts, the lower margin of said wall sheet bent inwardly and secured to said leg, said wall sheet extending between and secured to said posts.

5. A wall for a railway car comprising a bottom chord having an upstanding leg, a top chord having a depending arm, spaced tubular posts with the lower ends thereof slotted and straddling said leg and secured thereto on both sides thereof, and a wall sheet having the major portion thereof substantially in the plane of the outside of said posts, the lower margin of said wall sheet bent inwardly and secured to said leg and the upper margin of said wall sheet bent inwardly and secured to said arm, said wall sheet extending between and secured to said posts.
